UNITED STATES PATENT OFFICE.

IRWIN A. SEIDERS, OF READING, PENNSYLVANIA, ASSIGNEE OF ONE-HALF TO HIMSELF
AND ONE-HALF TO AGNEW T. DICE, JR., OF READING, PENNSYLVANIA.

LOCOMOTIVE.

1,269,322.

Specification of Letters Patent. Patented June 11, 1918.

Application filed July 8, 1916. Serial No. 102,088.

To all whom it may concern:

Be it known that I, IRWIN A. SEIDERS, a citizen of the United States of America, residing in Reading, in the county of Berks, in the State of Pennsylvania, have invented certain new and useful Improvements in Locomotives, of which the following is a true and exact description, reference being had to the accompanying drawings, which 10 form a part thereof.

My present invention comprises improvements in the construction of a locomotive having superheating provisions, the improvements being devised with the general 15 object of preventing objectionable spark discharge from the locomotive smoke stack and at the same time securing a desirable locomotive draft. More specifically, the object of my present invention is to provide a 20 simple and advantageous adaptation to locomotives with superheating provisions of essential and characteristic features of my invention in locomotive front ends disclosed and claimed in Patent No. 1,174,628, granted 25 March 7, 1916.

The various features of novelty which characterize my invention are pointed out with particularity in the claims annexed to and forming a part of this specification. 30 For a better understanding of the invention, however, and the advantages possessed by it, reference should be had to the accompanying drawings and descriptive matter in which I have illustrated and described 35 preferred embodiments of my invention.

Of the drawings:

Figure 1 is a sectional elevation of a portion of a locomotive embodying my present invention; 40 Fig. 2 is a front end elevation of the locomotive shown in Fig. 1 with parts broken away and in section; and Fig. 3 is a view taken similarly to Fig. 1 showing a somewhat different construction.

In the drawings and referring first to the construction shown in Fig. 1, A represents the boiler shell of a locomotive; B the front tube sheet thereof; C the fire tubes in which 50 the superheater pipes T are inserted, and CA the smaller fire tubes not containing superheater pipes and located below and at the sides of the bank of tubes C. The fire tubes C and CA open into the smoke box D from the upper end of which the smoke

stack E leads. Located in the smoke box D are an exhaust pot G, an exhaust nozzle proper G' and a chambered head or superheater T U of usual construction to which the superheater pipes T are connected and from which the usual steam pipes F run to the engine cylinder.

Also located within the smoke box D are provisions for preventing the emission of sparks from the locomotive smoke stack E. 65 These provisions, as shown, are substantially identical with the spark arresting provisions disclosed in the said Patent No. 1,174,628. As shown in Figs. 1 and 2, the spark arresting provisions comprise a spark breaker plate H extending across the smoke box D approximately between the levels of the upper and the lower edges of the bank of fire tubes C. As shown, the spark breaker plate H is connected at its upper edge to a 70 horizontal plate I B which may be connected in turn at its ends to the opposite sides of the boiler shell as by means of the brackets I¹⁰ and is connected at its rear edge to a vertical plate I A which is secured at its upper edge 75 to the chambered head U in front of the superheater pipes T. The spark breaker plate H in the particular form shown is provided with apertures H³ formed by punching out tongues H² which project from 80 the surface of the plate and are downwardly inclined to deflect cinders or coals passing through the apertures H³ toward the bottom of the smoke box. Between the rear edge of the body of the superheater T U 85 and the tube sheet B is interposed a horizontal plate I which is shown as connected to the tube sheet by means of an angle bar J.

The smoke box of the locomotive is divided into an inlet compartment receiving 90 the hot gases issuing from the fire tubes, and an outlet compartment open to the smoke stack E. These compartments are separated by a pervious or screen wall which in the preferred construction illustrated 100 comprises a table M having two downwardly inclined side sections formed of sheet metal and a horizontal bottom section m. The latter seats upon and is clamped to the exhaust pot G and is apertured to form a 105 screen through which small particles may pass. The table M is connected to the boiler shell at its ends. The usual live steam supply pipe g for the nozzle G' is preferably located below the table M. A screen or 110

wire netting or perforated metal L extends parallel to the spark breaker plate H in front of the latter and is connected at its lower edge to the rear edge of the table 5 M, and has its upper edge clamped against a downturned flange portion of the plate IB. The side edges of the netting L between the upper edges of the table M and the ends of the plate IB are secured to the boiler shell. 10 A spark arresting screen LA extends from the front edge of the table M to the top and sides of the boiler shell. This screen preferably comprises a main section and a removable door section LB. The branches of the 15 steam pipe F pass through apertures formed in the inclined portion of the table M, suitable provisions being made for preventing the passage of cinders or sparks along the joints between the steam pipes and the walls 20 of the apertures in the table M. Located in the outlet compartment of the smoke box between the front and rear screens LA and L is a chimney or mixing nozzle R formed as shown with an enlarged lower portion R' 25 and an axially adjustable upper or telescopic connection R². The chimney R is held in place by brackets S' secured to the metal sides S extending between the table M at the opposite side edges of the perforated portion m, and the portion of the 30 stack E which extends into the upper end of the smoke box.

When superheated steam is not being used it is necessary or at least highly desirable 35 to prevent the free passage of the gaseous products of combustion from the fire box through the fire tubes C. For the purpose of regulating the flow through the fire tubes C, a downwardly inclined baffle or partition 40 plate V has its rear upper edge secured to the tube sheet B at a level between the bottom row of fire tubes CA and the upper row of fire tubes C. Also projecting forwardly from the tube sheet B at the opposite sides 45 of the bank of fire tubes C are two vertical partition plates VA. Located between the front edge of the baffle or partition V and the lower edge of the plate IA and between the plates VA, are damper provisions which, 50 as shown, comprise a plurality of dampers W. The dampers W are shown as formed with trunnion like end portions W' journaled in the partition walls VA. The dampers W are connected for simultaneous 55 operation by means of crank arms W² and links W³. Advantageously, means are provided for automatically turning the dampers W into the horizontal open position indicated in dotted lines in Fig. 1 when superheated steam is being used, and when superheated steam is not being used, for moving the dampers into the closed position shown in full lines in Fig. 1. For this purpose one 60 of the damper shafts W is shown as extended through the locomotive shell and con-

nected to an external automatic damper operating device X of a well known type.

In the closed position of the dampers W they serve in conjunction with the plates I, IA, V and VA, and the superheater T U, 70 to prevent the passage of hot gases through the tubes C. At this time all the products of combustion from the combustion chamber of the locomotive boiler pass through the fire tubes CA lying below and at the sides 75 of the tubes C. When superheated steam is being used and the dampers W are in the open position the gaseous products of combustion pass through the fire tubes C as well as through the fire tubes CA.

In operation, when superheated steam is being used and the dampers W are in the open position, the gaseous products of combustion passing through the fire tubes C impinge against the spark breaker plate H, 80 and, if already small enough, pass through the apertures H³, or are broken up by the impact so that they may pass through the apertures or are deflected to the lower end of the smoke box below the level of the table 90 M. The solid material passing into the screen space surrounding the chimney R is either swept out of the smoke stack by the draft, or collects on the table M and rattles down on the perforated portion m of the 95 latter. From the table portion m, the suction created by the exhaust discharge from the exhaust pot G sweeps these particles, all of which are fine enough to be removed by the draft, up through the chimney R and 100 out of the smoke box through the smoke stack E. The cinders and fuel particles passing out of the flues CA when the dampers W are in their open position are, if of any appreciable size and weight, for the 105 most part broken up by their impingement against the exhaust pot G or against the sides and front end wall of the smoke box. The particles of solid material collecting on the inner wall of the boiler shell below the 110 table M are continually being sucked up through the apertured portion m of the table M and drawn out of the smoke box through the chimney R and stack E, especially as in the usual operation of the locomotive, the particles tending to collect on the bottom wall of the shell are continuously 115 being tossed about with the result of breaking up the portions not broken small enough by the spark breaker plate H to pass through 120 the screens L and LA and the apertured portion of the table M.

When superheated steam is not being used and the dampers W are in their closed position, a portion of the gaseous products of 125 combustion issuing from the front ends of the fire tubes CA may pass up into the space between the dampers and the spark breaker plate H and thence through the apertures of the latter and the rear screen L into the 130

outlet compartment of the smoke box. This has the advantage of reducing the frictional resistance to the flow through the smoke box of the gaseous products of combustion passing through the fire tubes CA at the time when all the gaseous products from the combustion chamber of the boiler must pass through the fire tubes CA.

With the construction described the important practical advantages characterizing the invention of the prior Patent No. 1,174,623, of simplicity, mechanical strength, durability, easy maintenance of tight joints, ease of and accessibility for inspection, adjustment and repairs, and the effective prevention of an undesirable discharge of sparks through the smoke stack are obtained, and these advantages are obtained without appreciable interference with a direct draft and without requiring a small exhaust nozzle and large back pressure, and insure the same good combustion and consequent decrease in coal consumption with a locomotive having superheating provisions which have heretofore characterized the practical use of the invention of the earlier patent. At the same time the present invention gives the special advantages with superheating locomotives to which reference has already been made.

In the modified construction shown in Fig. 3, the advantages of the construction shown in Figs. 1 and 2 are obtained to a substantial degree with a somewhat simpler construction. The construction shown in Fig. 3 differs from that shown in Figs. 1 and 2 essentially in that a single damper WA is employed and in that the plate IC corresponding generally in its location and purpose to the plate IA of the construction first described, is extended downward to a considerably greater distance. In consequence the spark breaker plate HA and the rear screen L¹⁰ of the construction shown in Fig. 45 3, are of less vertical depth than the general corresponding spark breaker plate H and screen L of the construction first described. With the construction shown in Fig. 3, however, a fairly direct draft is obtained without the complication of a plurality of dampers. The single damper WA of the construction shown in Fig. 3 is pivoted slightly in front of the tube sheet C and swings across the spark breaker plate HA as it is moved from its closed to its wide open position. The baffle plate VB of Fig. 3 is substantially narrower than the plate V of the construction shown in Fig. 1.

While in accordance with the provisions of the statutes I have illustrated and described the best forms of my invention now known to me, it will be apparent to those

skilled in the art that changes can be made in the form of my invention without departing from its spirit, and that some features of my invention can be used without a corresponding use of other features.

Having now described my invention, what I claim as new and desire to secure by Letters Patent, is:—

70

1. In a locomotive, the combination with the boiler shell, the tube sheet dividing the steam and water space of the locomotive from the smoke box, the smoke stack outlet, the fire tubes connected to said tube sheet, the exhaust nozzle located in the lower portion of the smoke box, the superheater pipes located in some of said tubes, and the chambered superheater header, a spark breaker plate and damper mechanism adapted when open to permit the direct passage from said mechanism into contact with the said spark breaker plate of products of combustion issuing from the fire tubes containing superheater pipes and to divert away from said plate the gaseous products of combustion issuing from the fire tubes not containing superheater pipes, and adapted when closed to permit the products issuing from the fire tubes not containing superheater pipes to pass into direct contact with said spark breaker plate while preventing the passage of gaseous products of combustion through the fire tubes containing superheater pipes.

2. In a locomotive, the combination with the boiler shell, a tube sheet dividing the steam and water space of the locomotive from the smoke box, the smoke stack outlet, the fire tubes connected to said tube sheet, the exhaust nozzle located in the lower portion of the smoke box, the superheater pipes located in the upper fire tubes and the chambered superheater header, of a screen system extending across the smoke box between the said tube sheet and said smoke stack outlet and comprising a substantially vertical portion lying in front of the fire tubes, a perforated spark breaker plate lying to the rear of said screen portion and a damper mechanism adapted, when open, to direct the gaseous products issuing from the fire tubes containing superheater pipes against said spark breaker plate and to divert the gaseous products issuing from the other fire tubes away from the said spark breaker plate, and adapted, when closed, to prevent the passage through the fire tubes containing superheater pipes of gaseous products of combustion without interfering with the passage of gaseous products issuing from the fire tubes not containing superheater pipes into direct engagement with said spark breaker plate.

IRWIN A. SEIDERS.
